ALBERT BROADMEYER, OF HARRISBURG, PENNSYLVANIA, ASSIGNOR TO W. O. HICKOK MANUFACTURING COMPANY, OF HARRISBURG, PENNSYLVANIA, A CORPORATION OF PENNSYLVANIA

SHEET FEEDING APPARATUS

Application filed July 30, 1930. Serial No. 471,713.

In sheet feeding mechanism in which a support for a plurality of sheets, such for example as a vertically moving table is employed, a conveyor is provided for carrying the sheets away from the feeding mechanism, and alongside this conveyor a guide is ordinarily employed in order that the line of sheets may be properly directed to the succeeding instrumentality, such as a ruling machine, folder, or the like. Various mechanisms have been employed for insuring the bringing of the sheets against the guide as they are conveyed.

In the individual feeding of paper sheets from a pile, trouble is experienced by reason of the fact that the sheets will adhere so that the topmost sheet will carry with it the underlying sheet. This is due to a variety of causes, among which is the fact that the sheets travel in line with the grain of the paper and there is a drag of one sheet upon the other caused thereby. In hand feeding the sheets are usually each drawn backwardly from the pile before feeding forwardly to overcome this tendency.

One of the important objects of the present invention is to provide mechanism that will feed sheets diagonally from a pile and consequently at an angle to the grain of the paper, thereby materially overcoming the difficulty above indicated.

Another important object of the present invention is to provide a feeder in which the means that removes the sheets from the support, will direct them not only toward the conveyor, but also toward the guide, thus performing a double function.

Still another object is to provide in connection with the sheet removing means, co-operating air blast means for raising the upper sheets toward the removing device, said means operating at the corner of the pile, at which place separation will occur much more easily, and therefore further minimizing the liability of more than one sheet being fed at a time.

In the accompanying drawings:

Figure 1 is a side elevation of the preferred embodiment of construction.

Figure 2 is a top plan view of the same.

Figure 3 is a longitudinal sectional view on the line 3—3 of Figure 2.

Figure 4 is a longitudinal sectional view on the line 4—4 of Figure 2.

Figure 5 is a detail view showing more particularly the drive shaft connection for the suction roller.

Figure 6 is a perspective view of the suction roller and air blast nozzles and their relation to the pile of sheets.

In the embodiment disclosed, a suitable frame 7 is employed, in which is mounted a vertically movable table 8 for a pile of sheets, as 9. This table is supported by sprocket chains 10 operating over sprocket wheels 11 on shafts 12 that are journaled on the frame. The shafts 12 carry worm wheels 13 engaged by worms on a cross shaft 14. The shaft 14 is also provided with a ratchet wheel 15 on which operates a pawl 16 pivoted on a pawl carrier 17 that is journaled on the shaft 14. The pawl carrier is oscillated by a link 18 having a loose play connection 19 with the pawl carrier and having a crank mounting 20 on a crank disk 21. Obviously as the crank disk 21 rotates, the pawl carrier 17 will, unless otherwise prevented, have an oscillatory movement, thereby operating the pawl 16 and causing it to intermittently rotate the ratchet wheel 15. This rotates the shaft 14, turning the worm wheels 13, shafts 12 and the sprocket wheels 11. As a consequence the chains 10 are drawn upwardly, elevating the table.

In order to control the upward movement of the table by this ratchet mechanism, the pawl carrier 17 is provided with a stop finger 22, and a detent finger 23, pivoted at 24, is adapted to swing to and from a position beneath the finger 22. The movement of the detent finger 23 is controlled by a link 24a pivoted thereto and pivoted to a crank arm 25 on a rock shaft 26. The rock shaft has a forwardly extending arm 27 provided with a feeler 28 that rests on the rear portion of the pile 9. This arm 27 is preferably counterweighted as shown at 29. Obviously, therefore when the top of the pile reaches a sufficient height, the feeler 28 and arm 27 are elevated, thereby moving the link 100

24^a in a direction to cause the detent 23 to be located beneath the finger 22. The pawl carrier 17 cannot therefore oscillate but the loose play connection 19 of the driving link 5 18 allows the latter to move. When the top of the pile is lowered, due to the removal of the sheets, the feeler 28 will drop, thereby causing the link 24^a to withdraw the detent 23 from beneath the finger 22 and leaving 10 the pawl carrier 17 free to oscillate sufficiently to cause the pawl to alternately ride over the teeth of the ratchet wheels 15, and thereafter engage the same and turn said ratchet wheel with a consequent elevation of 15 the table.

Extending from the rear side of the frame 7 is a sheet conveyor, including endless tapes 30 for carrying the sheets away from the pile support. These tapes pass around a front 20 roll 31 and a rear roll 32. Coacting with the roll 31 are the usual pressure rolls 33 that serve to cause the sheets delivered from the pile, to be frictionally engaged and carried on to the conveyor tapes 30. Located along- 25 side the conveyor, preferably on the front side of the machine, is a guide bar 34, against which the edges of the sheets engage, the stream of sheets thereby being positioned to pass on into the succeeding instrumentality 30 that operates on them.

Means are provided in the present embodiment for removing the sheets from the pile and delivering them not only toward the conveyor, but also toward the opposite guide 34. 35 To this end a supporting post 35 is mounted on one side of the frame and an arm 36 has a split collar 37 mounted on the post, so that the arm may be adjusted or swung to different positions on said post. A contracting 40 bolt 38, engaged with the split collar, serves to clamp the same and consequently the arm to the post 35. This arm 36 terminates at its free end in a contractile split collar 39 in which is a vertical rod 40 having rotatably 45 mounted on its lower end, a depending yoke 41. In this yoke is journaled a suction roller 42, which overlies the rear corner of the pile 9 that is adjacent to the guide 34. The yoke 41 can be clamped by contracting the collar 50 43, which embraces the rod 40.

The suction roller 42 is rotated by any suitable means, as for example, a flexible shaft 44 connected to a driving gear 45 in mesh with another gear 46 that is mounted 55 on the shaft carrying the roller 31. Extending from the suction roller 42 is the usual suction conduit 47 leading to the intake side of a suitable fan, indicated at 48. A valve 49 in the conduit 47, controls the suction through the roller 42 in a manner well understood, said valve being operated by suitable cam mechanism 50. Leading from the discharge side of the fan 48 is a conduit 51 connected to branches 52 (see Figure 6) 60 that terminate at nozzles 53. These nozzles

are located on the opposite sides of the corner of the pile 9, over which the suction roller 42 is located.

It will be understood that the elevation of the table and of the pile of sheets located thereon takes place in the well-known manner. That is to say, as the sheets are removed and the top of the pile thereby lowered, the table is automatically elevated until the top of the pile assumes its normal location. It 70 will also be understood that the suction roller as such operates in the usual manner to remove the topmost sheets successively. It will be noted, however, that this roller has its axis of rotation located diagonally or obliquely to 75 the pile, to the direction of movement of the conveyor and to the guide 34, and that as its underside rotates rearwardly, the sheets are picked up at their corners and are delivered 80 toward the conveyor and also toward the 85 guide 34. Consequently they are not only removed from the pile and delivered to the conveyor, but are brought toward and against the guide by the action of the suction roller. Because of the adjustable support, this 90 suction roller can be placed in varying positions and at different angles of inclination, making it adaptable for use on sheets of different sizes and on piles located at various distances 95 from the guide 34.

From the foregoing, it is thought that the construction, operation and many advantages of the herein described invention will be apparent to those skilled in the art, without further description and it will be understood 100 that various changes in the size, shape, proportion and minor details of construction may be resorted to without departing from the spirit or sacrificing any of the advantages 105 of the invention.

What I claim, is:

1. In a sheet feeding apparatus, the combination with a support for a plurality of sheets that permits their oblique movement thereover, of means behind the support for conveying the sheets rearwardly away from the support, a guide for the sheets carried by the conveyor and located behind the support and alongside the conveyor, and a device for removing sheets from the support and directing them diagonally of the conveying means and toward the guide as they advance toward the latter.

2. In a sheet feeding apparatus, the combination with a support for a plurality of sheets, of a conveyor behind the support for carrying the sheets away from the support, a guide for the sheets carried by the conveyor and located alongside the same and behind the support, and a suction device above the support for moving the sheets successively from the support rearwardly, obliquely of the conveyor and toward the guide.

3. In a sheet feeding apparatus, the combination with a support for a plurality of

5 sheets, of a conveyor behind the support for carrying the sheets away from the support, a guide for the sheets carried by the conveyor and located alongside said conveyor, and a suction roller for moving the sheets successively from the support and toward the guide, said roller having its axis of rotation disposed in a plane substantially parallel to the sheets and set obliquely to the direction in which 10 the conveyor moves and operating to move the sheets rearwardly to the conveyor and obliquely toward the guide.

4. In a sheet feeding apparatus, the combination with a support for a plurality of 15 sheets, of a conveyor for carrying sheets away from said support, a guide for the sheets so conveyed, a device for removing the sheets from the support, and directing them to the conveyor, and means for adjustably supporting the device for changing 20 its angularity of position to cause the device to direct the sheets toward the guide.

5. In a sheet feeding apparatus, the combination with a support for a plurality of 25 sheets, of a conveyor for carrying sheets away from said support, a guide for the sheets so conveyed, a suction roller for removing the sheets from the support and directing them to the conveyor, and a support for the roller 30 adjustable to permit it to be set obliquely to the conveyor and guide to direct the sheets toward the guide.

6. In a sheet feeding apparatus, the combination with a frame, a vertically movable 35 pile support therein, of a conveyor for carrying sheets away from the support, a guide located alongside the conveyor, a post mounted on the frame, an arm adjustably mounted on the post, and overhanging the support, a 40 yoke adjustably suspended from the arm, and a suction roller journaled in the yoke and operating to remove sheets successively from a pile on the support and deliver them toward the conveyor and guide.

45 7. In a sheet feeding apparatus, the combination with a frame, of a vertically movable pile support mounted thereon, a conveyor for carrying sheets away from the support, a guide located alongside the conveyor, a suction roller overlying the corner portion of the support adjacent the guide, means for adjustably mounting the suction roller to permit its axis of rotation to be adjusted to different degrees of angularity with 50 respect to the pile support, conveyor and guide, means for rotating the suction roller to cause it to deliver sheets to the conveyor and toward the guide, and means for directing a blast of air against the corner portion 55 of the pile overhung by the suction roller.

60 8. In combination with a support for a pile of sheets, of means behind the support for conveying the sheets rearwardly in flat condition from the pile, a guide for the sheets 65 located longitudinally of the conveying

means and behind the support, and a sheet delivering means that operates over the pile support and over the rear corner of the pile that is adjacent the conveyor and guide, said delivery means operating to move the sheets 70 obliquely of the pile support and to the conveyor and toward the guide.

9. In combination with a support for a pile of sheets, of means behind the pile on the support for conveying the sheets rearwardly 75 away from the pile, a guide for the sheets located longitudinally of the conveying means and behind the pile, a suction roller rotatable on a substantially horizontal axis that is oblique to the pile support and located over the rear corner of the pile that is adjacent the guide, and means for rotating the roller to cause its underside to operate on the corner portions of the sheets and obliquely of the pile move said sheets away from the pile support in an oblique direction and advance them to the conveyor and toward the guide.

In testimony whereof, I affix my signature.

ALBERT BROADMEYER.
